(57) **CLAIM**

The ornamental design for an incubator housing, as shown.

DESCRIPTION

FIG. 1 is a perspective view of an outside of the incubator housing.

FIG. 2 is a perspective view of an inside of the incubator housing of FIG. 1.

FIG. 3 is an inside view of the incubator housing of FIG. 1.

FIG. 4 is an outside view of the incubator housing of FIG. 1.

FIG. 5 is a [side] top view of the outside of the incubator housing of FIG. 1; [and,]

FIG. 6 is [another] side view of the outside of the incubator housing of FIG. 1[.];

FIG. 7 is a perspective view of an outside of a second embodiment of the incubator housing;

FIG. 8 is a perspective view of an inside of the incubator housing of FIG. 7;

FIG. 9 is an inside view of the incubator housing of FIG. 7;

FIG. 10 is an outside view of the incubator housing of FIG. 7;

FIG. 11 is a top view of the outside of the incubator housing of FIG. 7; and,

FIG. 12 is a side view of the outside of the incubator housing of FIG. 7.

The portions of the drawings in broken lines are shown for illustrative purposes only and form no part of the claimed design.

1 Claim, 10 Drawing Sheets

Matter enclosed in heavy brackets [ ] appears in the original patent but forms no part of this reissue; matter printed in italics indicates the additions made by reissue.
